GOVERNOR MECHANISM

Anthony F. Schwendner, Essington, Pa., assignor
to Westinghouse Electric & Manufacturing
Company, East Pittsburgh, Pa., a corporation
of Pennsylvania

Application June 7, 1934, Serial No. 729,370

16 Claims. (Cl. 264—14)

My invention relates to control apparatus for prime movers, for example, steam turbines, and it has for an object to provide a governing system which is stable and capable of operating with a small percentage of regulation.

A further object of my invention is to provide a governor of the pressure transformer type which utilizes a small range of primary fluid pressure change, the primary fluid pressure being developed as a function of the speed of the prime mover, to secure a large range of secondary or transformed fluid pressure used to actuate the governor or admission valve means.

A further object of my invention is to provide a prime mover governor of the fluid pressure type wherein fluid pressure developed as a function of the speed of the prime mover is applied to a sealed expandable chamber of transformer governing apparatus, whereby minimum flow of fluid under primary pressure is required.

A further object of my invention is to provide a pressure transformer wherein frictional resistance is minimized.

A further object of my invention is to provide a turbine installation having a governor valve, a throttle valve and an emergency governor, with a transformer governor constructed and arranged so that, in case of overspeeding of the turbine to a predetermined extent, not only is the throttle valve closed, but the transformed or secondary pressure utilized to actuate the governor valve is released, whereby closure of the governing valve is assured.

A further object of my invention is to provide a turbine installation, having a governor valve, a throttle valve, and an emergency governor with a transformer governor subject, respectively, both to a back pressure regulator and to primary pressure of fluid developed as a function of the speed of the turbine, the transformer governor being constructed and arranged so that, in case of overspeeding of the turbine, not only is the throttle valve closed, but also the transformed or secondary pressure is released to permit closure of the governor valve.

These and other objects are effected by my invention, as will be apparent from the following description and claims, taken in connection with the accompanying drawings, forming a part of this application, in which:

Fig. 1 is a diagrammatic view of an embodiment of my improved control system;

Fig. 2 is a view similar to Fig. 1 but showing a modified form of the control system;

Fig. 3 is a sectional view of the transformer governor shown in Fig. 1;

Fig. 4 is a sectional view of a transformer governor employed with the embodiment shown in Fig. 2;

Fig. 5 is a sectional view showing a modified form of pressure transformer;

Fig. 6 is a sectional view of the servo-motors of Fig. 2;

Fig. 7 is a diagrammatic view showing a further embodiment of my invention; and

Fig. 8 shows an alternative form of accumulator means.

Referring now to the drawings more in detail, I show a prime mover, for example, a steam turbine, at 10, including a stator 11 and a spindle 12. One or more admission valve devices are shown at 13, each device including an admission valve 14 and a servo-motor 15 for opening and closing the valve.

The turbine is provided with primary pressure-producing means, at 16, for developing fluid under primary pressure and varying as a function of the turbine speed, the fluid under primary pressure being supplied to a transformer governor, at 17, which, in turn, supplies fluid under transformed or secondary pressure to the servo-motors 15 of the admission or governor valves.

The transformer governor, at 17, is constructed and arranged to utilize a narrow range of primary pressure change to secure a very much wider range of secondary pressure change so that very small changes in primary pressure are effective to secure response of the steam valve.

The primary fluid pressure producing means, at 16, is constructed and arranged to provide such pressure with very little fluid flow so that power consumption for this purpose is minimized. Accordingly, I prefer to use the primary pressure producing means disclosed and claimed in the application of O. N. Bryant, Serial No. 728,257, filed May 31, 1934, and assigned to the Westinghouse Electric & Manufacturing Company and which pressure producing means will now be briefly described. The spindle 12 is provided with an impeller 18 of the centrifugal type supplying fluid under pressure to the annular chamber 19 provided in the stator structure, the annular chamber supplying fluid through an orifice 20 to the primary pressure passage 21 communicating with a centrifugal escape device comprised preferably by the annular chamber 22 and the diagonal passage 23 formed in the spindle.

One end of the passage 23 communicates continuously with the annular channel 22 and the

other end communicates with a drain. It will, therefore, be apparent that the pressure existing in the passage 21 and the annular chamber 22 will depend upon the spindle speed, for, the more rapid the rotation of the spindle, the greater will be the centrifugal effect of the oil column in the diagonal passage between the spindle axis and the channel 22; and, in consequence, the pressure in the passage 21 will be modulated to vary substantially as the square of the turbine speed.

The orifice 20 serves as means for supplying fluid under pressure to the passage 21, but it restricts the rate of flow so that pressure in the passage 21 may be varied as a function of the turbine speed in the manner just referred to. The other end of the passage 21 communicates with the transformer governor, at 17.

The transformer governor, at 17, includes a housing 25 having an upper chamber 26, an intermediate chamber 27, and a cylinder 28. A sylphon or bellows 29 has its upper end connected to the wall of the chamber 26 and its lower end connected to an abutment 30. A smaller bellows or sylphon 31 is connected, at its upper end, to the abutment 30 and, at its lower end, to the bottom wall of the chamber. Hence, the large and small sylphons 29 and 31, together with the housing 25, provide a sealed primary pressure chamber 32 with which the primary pressure line 21 communicates, whereby negligible flow of fluid under primary pressure is required so that, not only are impulses quickly transmitted, but the power requirements of the primary pressure producing means are minimized.

As the sylphon 31 is of smaller diameter than the upper sylphon 29, it will be apparent that a lower annular primary piston area 33 is provided by the lower face of the abutment element 30, the primary pressure supplied by the line 21 being effective against the annular piston area 33 to secure upward movement of the abutment 30 and the lower end of the sylphon 29. This upward movement is resisted by a spring 34 whose compression is varied by a movable spring abutment 35; and means, such as a screw member 36, is provided for moving the abutment upwardly and downwardly, the screw being turned in any suitable manner by a speed changer motor 37.

A spinner piston valve 38 fits the valve cylinder 28 and it has upper and lower piston valve portions 40 and 41 separated by the annular space 42. (See Figs. 3 and 4.) The lower piston portion 41 normally just laps a pressure supply port 43 connected to the pressure supply passage 44; the intermediate annular space 42 continuously communicates with the secondary pressure supply passage 45; and the upper piston portion 40 laps the exhaust 46.

It will, therefore, be apparent that, with downward movement of the piston valve, the high pressure port 43 will be placed in communication, due to the annular space 42, with the secondary pressure supply passage 45 to increase the secondary or transformed pressure; and, with upward movement of the piston valve 38, the secondary or transformed pressure passage 45 will be placed in communication with the exhaust 46 connected to the drain system 47.

The spinner piston valve 38 extends vertically across the intermediate chamber 27 through the wall structure separating the intermediate and upper chambers, and within the small sylphon 31 to contact with the abutment 30, the upper end of the piston valve having a thrust bearing 48 pref-

erably having single point contact with respect to abutment structure 30. The spinner piston 38 is preferably maintained in contact with the abutment structure 30 due to the fact that secondary pressure is applied to the secondary or lower piston area 49 at the lower end of the piston valve 38.

The thrust bearing between the abutment 30 and the spinner piston valve 38 has minimum pressure exerted thereon, with the result that a very efficient thrust bearing, preferably of the point type may be used. The reason for this is that the abutment structure 30 has the opposed primary fluid pressure and spring forces applied thereto without such forces being imposed on the thrust bearing, the thrust bearing merely having to carry sufficient load to move the piston valve when the abutment structure moves in a direction toward the spinner piston valve, fluid pressure being utilized to cause the spinner piston valve to follow the motion of the abutment when the latter moves in the opposite direction. Hence, as the thrust bearing is subject to minimum load, minimum resistance to rotation of the spinner valve occurs.

Thus, it will be seen that the piston valve 38 tends to assume an equilibrium position in which the forces of the primary and secondary pressures applied to the primary and secondary piston areas 33 and 49, respectively, are counterbalanced by the force of the spring 34. If there is a change in primary pressure, then the equilibrium of forces is disturbed, and, consequently, the piston valve 38 moves to secure modification of the secondary or transformed pressure, the latter operation continuing until the change in secondary pressure is sufficient to compensate for the change in primary pressure when the piston valve will be restored to neutral or cut-off position.

From the transformer governor structure so far described, it will be apparent that an increase in primary pressure tends to move the abutment 30 upwardly, the spinner piston valve 38 following the abutment, but upward movement of the piston valve brings about reduction in secondary pressure, and, consequently, reduction in the pressure applied to the secondary piston face 49, this reduction in secondary pressure continuing until the force of the secondary pressure acting on the secondary face 49 is sufficiently reduced so that the spring 34 acting against the force of the primary pressure applied to the primary piston area 33 may move the piston valve 38 downwardly to its normal or neutral position.

If there is a reduction in primary pressure, the spring causes the abutment 30 to move downwardly, the piston valve 38 being pushed downwardly, and the secondary pressure supply passage being placed in communication with the high pressure port 43, whereupon there will follow an increase in secondary pressure, the secondary pressure increasing until the force thereof acting on the secondary pressure face 49 is sufficient to compensate for the reduction in primary pressure force acting on the primary piston face 33 in order that the spring and the fluid pressure forces may again be in equilibrium, at which time the piston valve 38 will be in neutral cut-off position.

The secondary pressure supply passage 45 is connected to the admission valve servo-motors 15.

To overcome static friction and to make the transformer governor more effective, the pilot valve is provided with turbine means to secure continuous spinning thereof. To this end, the 75

pilot valve has a rotor 50 against which is impinged motive fluid by the jet 50', the jet 50' being supplied from any suitable source, for example, from the high pressure passage 44.

5 An important feature of the present invention is to provide a governor which is highly responsive to load change. To this end, the secondary pressure applied to the secondary piston area 49 of the transformer is modified. The secondary 10 or transformed fluid under pressure is supplied through an orifice 51 to the space or expandible chamber 52 below the secondary piston face or area 49, and an air chamber or bell 53 is in communication with the space 52. Preferably, the 15 orifice area is adjusted by means of the needle valve 54.

For a given load, it will be apparent that there will be primary and secondary pressures which are related as determined by the primary and 20 secondary piston areas, the secondary pressure also existing in the space below the secondary piston area or face and in the air chamber. If there is a gradual change in load, the piston 25 valve 38 follows the motion of the abutment structure 30 so that the secondary pressure changes in accordance with the change in primary pressure without lag; however, with rapid change in load, and consequently with rapid 30 change in primary pressure, flow through the needle valve orifice is not sufficiently rapid to cause the pressure applied to the secondary piston face to change as rapidly as does the primary pressure, with the result that the pressure 35 acting on the secondary piston face or area is effective, with the primary pressure, to produce over-travel of the piston valve and thereby to produce a greater extent of secondary pressure change than would be called for by the change in primary pressure. For example, assume a 40 rapid drop in load, the turbine speed and the primary pressure rapidly increase and the sylphon moves upwardly in consequence thereof. The piston valve follows the motion of the sylphon causing reduction in secondary pressure; 45 however, due to the needle valve orifice, the pressure below the secondary piston face or area 49 cannot decline so rapidly, with the result that increased effort is applied to the piston valve to move the latter upwardly to reduce the 50 secondary pressure quickly, the reduction in secondary pressure being carried to a greater extent than would be called for by the primary pressure change. The governor valve may, therefore, be closed before the closing speed is 55 reached.

In other words, in this way, the governor is made responsive to the rate of change of speed so as to have an anticipating effect. With drop in load, as the device responds to the rate of change of speed, the governor valve may be operated upon before a change of substantial magnitude is attained. With drop in load, at a sufficiently rapid rate, the steam supply may be entirely cut off, thereby preventing further acceleration of the rotor and allowing for the valve to be reset to a position to permit enough steam to be supplied to maintain the speed of the turbine for the load carried.

If there is a sudden increase in load, then the 70 consequent sudden decrease in primary pressure causes the spring 34 to move the piston valve 38 downwardly, causing the secondary pressure to increase more rapidly than the pressure supplied to the secondary piston area or 75 face 49, and, consequently, the piston valve tends

to move downwardly more than it would if the secondary pressure built up rapidly below the secondary piston face or area. In other words, there would be a tendency for downward over-travel, and this would quickly bring about a 5 change in secondary pressure to a greater extent than called for by the primary pressure change. The governor valve may, for example, move to wide open position so as to suddenly provide an increased supply of motive steam to 10 the turbine, the governor valve then being reset by the transformer as the primary and secondary pressures are brought into normal relation with the secondary pressure applied to the secondary piston area 48 and the primary pressure 15 attaining a value corresponding to the speed for the load carried.

As soon as permitted by flow through the needle valve orifice, pressure below the secondary piston face or area 49 comes into equilibrium 20 with the secondary pressure, and this causes such motion of the piston valve that the secondary pressure is changed to adjust the governor valve to a position corresponding to its normal speed at the existing load point. In other words, 25 the needle valve orifice and the air chamber cause operation in response to rate of change of speed so that the required operation, depending upon the direction of change, occurs before substantial change in magnitude. For example, 30 the device may respond within a speed difference of a turn or a fraction of a turn of the spindle. On the other hand, if the device depended upon the extent or magnitude of change, the element of anticipation and consequent quick response 35 would be absent—there would be overspeeding with drop in load and too great a speed drop with sudden increase in load. The action in response to rate of speed change causes the governor valve to close before the turbine reaches 40 closing speed and to open wide before the speed drops to a point corresponding to wide open position of the valve.

In addition to the orifice and the air chamber or accumulator serving as an anticipator, these 45 features introduce a time element in the operation of the mechanism preventing hunting and violent fluctuations in the secondary or transformed pressure line. The adjustable orifice 51 restricts the rate of flow of secondary pressure 50 to or from the expandible chamber 52 formed in part by the secondary piston face 49. The orifice 51 and the air chamber 53 work together to provide a desired time interval during which pressure change occurs in the secondary expandible chamber 52. When the apparatus is installed, the orifice needle valve 54 is adjusted for 55 best operation and then it is locked in place.

The high pressure passage 44 is supplied from a high pressure line or system 55 supplied by the 60 pump 56. Fluid under high pressure is preferably furnished from the line 55 for actuation of the servo-motor or motors 15.

In addition to the motive steam having to pass through the admission valve or valves 14, such 65 steam must also pass in the usual way through a throttle valve 57, the throttle valve being opened and closed by a stem 58 connected to a piston 59 arranged in a cylinder 60. A spring 61 is arranged in the cylinder 60 above the piston and fluid pressure is supplied through the port 62 to the space below the piston 59 to raise the latter against the force of the spring 61. Fluid under pressure is supplied to the port 62 by a passage 75

63 connected to the high pressure line 55 through an orifice 64.

The passage 63 has a branch 65 going to the trip valve 66 of the autostop or emergency governing mechanism, at 67, and a branch 68 going to the trip valve, at 69, the apparatus operating so that, when the emergency governor is effective, the pressure in the line 63 is suddenly reduced, the orifice 64 preventing rapid replenishment thereof, so that the spring of the throttle valve is effective to secure sudden closure thereof and the trip valve, at 69, is operated as hereinafter pointed out.

The autostop or emergency governor is of the usual type, the turbine spindle 12 being provided with a diametrically extending pin 70 in the diametrically-extending chamber 71 and the pin is held normally in inactive position by a spring 72. The center of gravity of the pin 70 is arranged sufficiently eccentric and the spring 72 of such force is chosen that, when a predetermined overspeed of the turbine is attained, the pin 70 suddenly flies radially outward, thereby acting on the tripping mechanism, at 73, to release pressure applied to the spring 74 to hold the valve 66 closed, whereupon the latter valve opens, thereby permitting of release of pressure in the orifice line 63 and the branches 65 and 68 for the purposes just stated.

Referring to the trip valve, at 69, this comprises an upper cylinder 76 and a somewhat shorter lower cylinder 77 of larger diameter than the cylinder 76. A piston valve 78 is arranged in the cylinders. The secondary or transformed pressure supply line 45 is provided with a release passage 79, which communicates with the upper portion of the cylinder 76. A drain passage 80 communicates with the cylinder 76 a suitable distance below the point of communication of the release passage 79 so that the piston portion 81 of the piston valve 78 is normally effective to interrupt communication between the passages 79 and 80; however, as hereinafter pointed out, with downward movement of the piston valve 78, the secondary release passage 79 is placed in communication with the drain, whereupon the secondary or transformed pressure in the line 45 is released in order to bring about closure of the servo-motor or motors of the admission valves.

Both the high pressure line 55 and the high pressure passage 44 communicate with the cylinder 76, the point of communication being preferably at the same level and piston portions 82 and 83, with the annular space 84 therebetween preferably normally affording communication between the high pressure passage 55 and the supply passage 44, but, with downward movement of the piston valve 78, the piston portion 82 interrupts such communication, thereby cutting off the supply of high pressure fluid to the transformer governor.

The piston valve 78 has connected to the lower end thereof a piston 86 arranged in the lower cylinder 77, a spring 87 preferably acting downwardly on the piston and the piston being forced upwardly by the force of fluid pressure supplied by the branch 68 of the orifice line 63. Thus, it will be seen that, upon release of the orifice line pressure, not only will the throttle valve close, but also the pilot valve 78 of the trip device, at 69, will move downwardly to release the secondary or transformed pressure and to interrupt the supply of high pressure fluid to the transformer governor.

The servo-motors, at 15, may be of any suit-

able type so long as they are effective to bring about closure of the governor or admission valves upon drop in secondary or transformed pressure. To this end, in Fig. 1, I show the servo-motor 15 comprised by a housing having an operating cylinder 88 with an operating piston 89 therein, a spring 90 being disposed above the piston to exert its force thereon. The piston 89 is moved by fluid pressure applied to its lower face in the manner to be pointed out, increase in fluid pressure causing upward movement of the operating piston 89 until the fluid pressure force is in equilibrium with the force of the spring 90 and reduction in fluid pressure force applied below the piston 89 causing downward movement of the piston under influence of the spring force.

Referring now to the means for applying and modifying fluid pressure applied to the operating piston 89, it will be seen that the secondary pressure supply line 45 communicates with the annular space 91 formed at the lower portion of the servo-motor housing or cylinder, the governor valve stem 92 extending through the annular portion. The valve stem or rod 92 has radial passages 93 communicating with an axial passage 94 to afford communication between the annular space 91 and the interior cylinder 95 of the operating piston structure.

A passage 96 communicates with the space below the operating piston 89 and the interior 30 of the cylinder 95 and a passage 97 communicates with the cylinder 95 at a point below the point of communication therewith of the passage 96 and it communicates with the annular space 98 formed about the operating piston. 35

A pilot valve 99 is arranged in the cylinder 95, a scale spring 100 being disposed in the cylinder and tending normally to move the pilot valve 99 downwardly. The pilot valve 99 is moved upwardly against the force of the spring 100 40 by secondary pressure applied through the passage 94 and acting against the lower piston portion 101 carried by the pilot valve. The passage 96 is normally lapped by an intermediate piston portion 102 of the pilot valve. With upward 45 movement of the pilot valve in response to an increase in secondary pressure, ensuing as a result of decrease in primary pressure with increase in turbine load and speed thereof, the pilot valve moves upwardly to establish communication between the high pressure space 98 encompassing the operating piston and the passage 96 communicating with the space below the operating piston, whereby the operating piston is raised by the high pressure supplied from the high pressure line 56 until such time as the piston portion 102 interrupts communication between the passages 97 and 96. On the other hand, with a decrease in secondary pressure, the pilot valve moves downwardly to place the passage 96 in communication, through the port 103, 55 with the space above the piston valve, the latter space being connected with the drain 47; and, thereupon, the operating piston moves downwardly until communication with the space below the operating piston, through the passage 96, is again interrupted. With release of the secondary pressure, due to opening of the passage 79, in the manner already referred to, it will be apparent that the operating piston will move under 60 the influence of its spring 90 to close the admission valve. Since the position of the pilot valve is dependent upon the magnitude of secondary pressure, the operating piston following the motion of the pilot valve to secure neutral 65

70 75

or cut-off position of the latter, it will be apparent that the spring force and, therefore, the secondary pressure, vary from a minimum to a maximum for complete movement in one direction of the operating piston and the connected valve and from maximum to minimum for complete movement in the other direction. Accordingly, the spring 100 serves the required function of a scale spring customarily employed in 10 a governing system.

The apparatus shown in Fig. 2 is generally similar to that already described, except that the transformer governor, at 17, in addition to having primary pressure imposed thereon by the 15 primary pressure line 21, also has tertiary pressure applied thereto and derived from a back pressure regulator, at 106. Furthermore, different types of operating devices or servo-motors for the admission valves are shown at 15a. In 20 addition, the secondary pressure release operative in response to autostop or emergency governor is modified.

Referring first to the back pressure regulator at 106, this may be of any suitable type provided 25 that requisite sensitivity is afforded. I prefer to use a regulator of the type shown and described in my application, Serial No. 729,372, filed June 7, 1934. Referring to Fig. 2, it will be noted that the regulator includes a housing 107 provided with upper and lower chambers 108 and 30 109 separated by body structure 110 providing a cylinder 111. A piston valve 112 is disposed in the cylinder and it is arranged to place the outlet passage 113 either in communication with 35 the inlet passage 114 supplied from the impeller chamber 19 or with the exhaust passage 115 communicating with the lower chamber 109, the latter chamber being connected to the drain 116. Hence, with upward movement of the piston valve 40 112, pressure in the outlet 113 will increase because of communication thereof with the pressure supply passage 114. On the other hand, with downward movement of the piston valve 112, pressure in the supply line 113 will decrease 45 because of communication thereof with the exhaust. The pressure line 113 communicates with the upper chamber 26 of the transformer governor so as to act on the upper face of the abutment 30 in the same direction as the 50 spring 34.

From the structure described, it will be apparent that the transformer governor, at 17, of Fig. 2 operates exactly in the same manner as the transformer governor in Fig. 1, except that 55 an additional fluid pressure is applied thereto, fluid pressure from the back pressure regulator, at 106, being supplied by the passage 113 to the space above the abutment 30. Therefore, not only does the transformer governor serve to control the admission of steam to the turbine in accordance with the load but also controls the admission so as to maintain a predetermined back pressure. It will be obvious that the back pressure regulator may be used in any suitable manner; it may be associated with the line between high and low pressure turbines, with an inter-stage bleeder line, or with the back pressure line 60 of a single turbine.

A back pressure steam connection 117 is connected, for example, to the connection 118 between high and low pressure turbine elements, the connection supplying steam to the chamber 119 so that its pressure may be exerted on the sylphon 120 arranged in the chamber, the sylphon 70 having a piston or abutment face 121 which

bears against a stem 122 carried by the abutment member 124, the latter bearing against the upper end of the spring 125 as well as against the pointed end 126 of the piston valve 112.

The lower end of the piston valve 112 has a point bearing connection 127 with respect to an abutment 128 against which bears a spring 129 arranged in the lower chamber 109. The lower end of the spring 129 is engaged by an adjustable abutment 130, the adjustment mechanism being 10 preferably constructed and arranged so as to prevent leakage on account of adjustment. For the latter purpose, the abutment 130 is preferably made cup-shaped as to enclose a bellows or sylphon 131 connected at its upper end to the abutment or follower 133 and at its lower end to the lowermost wall of the lower chamber 109. The sylphon, therefore, provides space to accommodate the adjustment screw or member 132, which may have a connection with respect to the lower wall which is sealed from the interior of the lower chamber 109.

From the back pressure regulator structure so far described, it will be apparent that the piston valve 112 is subject to opposing forces, the force 25 of the spring 129 acting upwardly on the piston valve 112 and the force of the steam pressure acting downwardly, through the sylphon abutment, on the pilot valve against the force of the spring 125.

The pilot valve has an upwardly facing piston face or area 133 to which fluid under outlet pressure is supplied through the passage 134 containing an orifice provided by the needle valve 136, the purpose thereof being to subject the 30 pilot valve to the effect of the outlet pressure. An accumulator, for example, an air bell 137 communicates with the passage 134 at the piston area side of the orifice. Outlet pressure acting on the piston area 133 tends to move the piston 35 valve 112 downwardly.

Assuming an increase in back pressure, then the sylphon abutment 121 causes downward movement of the piston valve 112 placing the impeller passage 113 in communication with the 40 exhaust 115, whereupon the pressure applied to the governing transformer abutment 30 will be decreased and the transformer governor will operate to restrict the supply of steam to the turbine. With a reduction in the outlet pressure 45 brought about in this way, the pressure applied to the piston face 133 is also reduced, whereby the total of forces tending to cause the piston valve to move downwardly is reduced, this reduction in outlet pressure continuing until the force thereof 50 acting on the piston face 133 is sufficient to counterbalance the back pressure force applied due to increase in fluid pressure, whereby the piston valve is brought back to a neutral cut-off position. On the other hand, with a decrease in pressure, the contrary operation takes place, the piston valve moving upwardly because of the reduced steam pressure acting on the sylphon abutment 121, thereby placing the impeller passage 55 114 in communication with the outlet passage 113 to increase the pressure thereof; and the pressure in the passage 113 will increase until such time as the increasing pressure applied to the piston face 133 is sufficient to compensate for 60 the diminishing steam pressure, whereupon the piston valve will be brought back to neutral or cut-off position.

The piston valve preferably has spinning motion imparted thereto by any suitable means, for 70 75

example, a turbine including a rotor 139 carried by the valve.

In Fig. 2, the autostop plunger 70 operates trigger mechanism 73 to permit a valve 66 to open in order to release the pressure in the orifice line 63, the latter having branches going to the throttle valve 57 and to the valve trip device, at 140, the latter preferably consisting of a valve 141 which normally closes a port 142 of the secondary pressure supply passage 45, the valve 141 having a piston 143 pressed downwardly by a spring 144 and having the orifice line 63 supplying pressure therebelow. With opening of the autostop or emergency governor valve 67, the pressure in the orifice line 63 is suddenly released, and the valve 141 moves downwardly under influence of the spring 144 to open the port 142 to drop the secondary or transformed pressure in the line 45.

In Figs. 2 and 6, there are shown servo-motor devices of a different type from that already described. Each servo-motor includes an operating piston 146 connected to a stem 146a, the stem being connected to the governor or admission valve. Each piston 146 is arranged in an operating cylinder 147 and the latter has spring means 148 therein and acting on top of the piston 146 so as to exert a biasing effect thereon tending to move the admission valve in a closing direction. The piston 146 is moved upwardly and downwardly by means of fluid under pressure supplied to and exhausted through the passages 149 and 150 and controlled by a piston valve 151.

The piston valve 151 is arranged in a valve cylinder 152 having upper and lower high pressure ports 153 and 154, respectively, adjacent to the ports 155 and 156 communicating with the passages 150 and 149, respectively. Fluid under high pressure is supplied from the high pressure line 55 to the high pressure ports 153 and 154. The piston valve 151 is provided with suitable piston portions 157, 158, 159 and 160 suitably spaced so as to afford communication with the ports, the piston portions 158 and 159 normally lapping the ports 155 and 156. If the piston valve moves upwardly, the upper passage 150 will be placed in communication with the exhaust port 161 and the lower passage 149 will be placed in communication with the high pressure supply port 154, whereupon the operating piston 146 is caused to move upwardly. On the other hand, if the piston valve 151 is moved downwardly, pressure will be exhausted from below the piston 146 and applied to the space thereabove.

Secondary pressure from the secondary pressure line 45 is supplied to a chamber 162 containing at its upper end a sylphon or bellows 163 having an abutment 164. A tension spring 165 is connected to the abutment 164 at one end and the other end of the spring is connected to a threaded screw 166, whereby the spring pull acting in opposition to the secondary pressure may be suitably varied.

The upper end of the piston valve is connected to the lower end of the tension or scale spring 167, the scale of the latter being substantially less than that of the spring 165, the upper end of the spring 167 being connected to one end of the follow-up lever 176, fulcrumed at an intermediate point 176a, the other end of the latter being pivotally connected to the valve rod 146a.

Assuming that there is a decrease in load and consequent increase in speed, the primary pressure delivered to the transformer increases and the secondary pressure delivered by the latter through the conduit 45 to the chamber 162 de-

creases. Therefore, due to this decrease in secondary pressure, the force thereof acting on the piston face 164 becomes less and the consequent preponderating force of the load spring 165 causes the pilot valve to be pulled down against the reduced secondary pressure and the tension of the scale spring 167 with the result that fluid under high pressure is supplied above the operating piston 146 and fluid below the latter is exhausted and the operating piston moves downwardly, such downward movement of the operating piston and movement of the admission valve in a closing direction continuing until such time as the increased tension force of the scale spring is sufficient to overcome the load spring to bring the pilot valve back to neutral or cut-off position.

On the other hand, should the turbine speed decrease due to increase in load, then the secondary pressure supplied to the chamber 162 would increase thereby causing the pilot valve to move upwardly, with increase in the tension force of the load spring 165 and decrease in the tension force of the scale spring 167; however, such movement of the pilot valve causes motive fluid to be admitted below the operating piston and the latter moves upwardly, and such upward movement of the operating piston will continue, the upward movement being accompanied by decrease in the tension force of the scale spring 167, until such time as the decrease in the tension force of the scale spring is sufficient to counteract the increase in tension force of the load spring 165, whereupon the pilot valve will be restored to neutral or cut-off position. The scale spring exerts maximum tension force with the admission valve in closed position and minimum tension force with the valve full open. In this way a scale effect is given to the governing system, there being a range of secondary pressures corresponding to the range of tension forces of the scale spring.

Thus, it will be seen that, under all conditions of operation, a change in secondary pressure is accompanied by movement of the pilot valve, such movement being resisted by the resultant of the tension forces of the load and scale springs and that the consequential movement of the operating piston results in follow-up motion being applied to the scale spring so that the tension force thereof is modified in such manner that the load spring may restore the pilot valve to neutral or cut-off position.

If desired, dash pot apparatus may be associated with the scale spring to avoid hunting effects. To this end, I show the upper end of the scale spring connected to a screw member 169, the latter being held between the head 170 of the stem 171, pivotally connected to the upper end of the follow-up lever 176, and a spring 172, the upper end of the spring 172 bearing against the bottom of the inverted cup-piston 175. The stem 171 extends through the bottom portion of the cup piston so that the spring 172 functions to hold the cup piston upwardly against suitable abutment means at 171a. The cup piston 175 fits within the cylinder 168 so that the space of the latter below the cup piston provides a displacement chamber. The cylinder has an adjustable orifice at 168a, which restricts to any desired extent the freedom of ingress and egress of fluid into and out of the displacement chamber. The dash pot arrangement prevents jerky or hunting movements of the apparatus. It is to be understood, of course, that the dash pot arrangement is an auxiliary device which may or may not be used, as desired, for the scale spring is fully effec-

tive to accomplish its intended purposes, as just pointed out, without having dash pot means associated therewith.

The dash pot comprised by the piston 174 and the cylinder 168 avoids jerky or hunting movements of the apparatus.

In Fig. 5, I show a further form of transformer governor wherein the impeller pressure is used as the source of supply for the transformed or secondary pressure. In this view, I show a housing structure 178 having an upper chamber 179, an intermediate chamber 180, and a cylinder having an upper portion 182 of larger diameter than a lower portion 183.

A sylphon or bellows 184 is disposed in the upper chamber and has its upper end connected to the wall thereof. The lower end of the sylphon has an abutment 185 engaging the point bearing 186 of the spinner piston valve structure 187. A compression spring 188 bears at its bottom against the abutment 185 and has its upper end engaged by a follower 189 which is adjusted upwardly and downwardly by the speed changer motor 190.

The piston valve structure 187 has an impeller or turbine element 191 arranged in the intermediate chamber 180, a piston portion 192 disposed in the cylinder portion 182 of larger diameter and defining a downwardly facing secondary piston face 193 and a piston portion 194.

Oil under primary pressure is supplied from the impeller to the passage 196 for action against the primary pressure face afforded by the sylphon. Also, fluid is supplied from the passage 196 to the jet 196a to impart spinning motion to the rotor 191 to avoid static friction of the piston valve structure.

With an increase in primary pressure, the sylphon abutment 185 will be caused to move upwardly; and, as the piston 194 has a groove 194a affording communication between the high pressure port and the space below the piston, primary pressure also acts upwardly on the lower face 195 of the piston portion 194, the spinner piston structure will thereby be caused to follow the motion of the sylphon, but, immediately upon such upward movement, a groove 197 cut in the piston element 192 affords communication of the secondary pressure space or passage 198 with the exhaust or drain, whereupon the secondary pressure declines, whereby the upward acting secondary force acting on the piston face 193 is reduced sufficiently so that the spring may overcome the increased primary force to move the piston valve 187 back to neutral or cut-off position. On the other hand, with a decrease in impeller pressure, the contrary operation takes place, the piston valve structure 187 moving downwardly under influence of the spring 188 due to decrease in impeller pressure, causing the groove 199 in the lower piston valve portion 194 to place the high pressure supply passage 200 in communication with the secondary passage 198, so as to increase the secondary or transformed pressure, this increase continuing until the increasing secondary pressure force acting on the piston face 193 in an upward direction is sufficient to counteract the diminishing primary pressure force acting on the sylphon 184.

Fig. 7 shows an embodiment similar to Fig. 1 but having features to suit it for base load operation. To this end, the transformed pressure line 45 between the transformer governor, at 17, and the servo-motor 15 is provided with an adjustable needle valve 201 providing a variable

orifice 202 and an air bell 203 is arranged between the needle valve and the servo-motor. This arrangement, while giving governor control of the base load machine, avoids response to frequency fluctuations. Where the turbine and its connected generator are used for base load operation, it is desirable to avoid disturbance of the governing system on account of frequency fluctuations, it being customary to have the base load generator connected to a system supplied by other generators. Frequency disturbances may, therefore, be imposed on the rotary parts of the base load machine and these disturbances would react on the governing system and the admission valve controlled thereby unless the arrangement shown in Fig. 7 were employed. While frequency fluctuations may produce fluctuations in secondary pressure supplied by the passage 45, the secondary pressure fluctuations are substantially damped or absorbed by the cooperation of the orifice 202 and the air chamber 203 arranged at the admission valve side of the orifice, whereby the governor is effective to control the admission valve to secure admission of steam suitable to load requirements without the latter being affected by frequency fluctuations.

With a transformer governor, such as shown in Fig. 1, and the needle valve 201 and the air bell or chamber 203 arranged in the line between the transformer governor and the servo-motor, it will be apparent that the governing system may be adjusted to suit any need. By opening the needle valve 201 and moving the needle valve 54 so as to restrict the orifice 51, the governing system will have an increased anticipating characteristic for reasons already pointed out. On the other hand, the system may be rendered more sluggish by opening the needle valve 54 so as to increase the size of the orifice 51 and by adjusting the needle valve 201 to restrict the orifice 202.

While I show, in Figs. 1, 2, 3, 4, and 7 accumulators of the air bell type, air chambers being shown at 53, 137 and 203, it will be apparent that other types of accumulator means may be used. For example, in Fig. 8, I show the expandible chamber for the piston area subject to secondary or outlet pressure formed in part by a bellows 205 whose expansion or distention is resisted by the spring 206, the force of the latter being varied by the follower 207 carried by the threaded stem 208. The bellows form is advantageous in that there is no chance of the accumulator becoming ineffective because of loss of air.

From the foregoing, it will be apparent that as the governing mechanism is of the pressure transformer type, it is highly sensitive to speed changes. Sensitivity of the transformer governor is increased by having a spinner piston valve and also by having such valve relieved of primary pressure and spring forces so that minimum pressure occurs in the thrust bearing between the spinner piston valve and the abutment structure subject to primary pressure and spring forces. Not only does the governing mechanism keep the admission valve means adjusted to admit the proper amount of steam to operate the turbine at the speed required for the load, but it may anticipate rapid changes in load so as to minimize changes in speed or be made to operate more sluggishly depending upon the need. Furthermore, the pressure transformer governor cooperates in peculiar ways with other elements of the power plant installation: the governor is

adapted to be acted upon by back pressure regulator, the operation being so sensitive that the regulator performs its function of holding the back pressure within a very narrow range of variation; the governor apparatus is peculiarly suitable for primary pressure developing means of low power consumption, this advantage following from the characteristic of the governor of being responsive to pressure change without requiring any flow on account of leakage; and the transformer, due to its particular arrangement of parts and connections, provides for an advantageously cooperative arrangement with pressure controlled parts of the plant such as the admission and throttle valves and the emergency governor, the pressure system or systems therefor being specially arranged to cooperate with features of the transformer governor.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In combination, means providing fluid under primary pressure; a cylinder having an inlet port supplied with fluid under pressure, an exhaust connection, and a secondary pressure port; means providing a supply passage communicating with the secondary pressure port; a piston valve movable from an intermediate cut-off position, in one direction, to establish communication of the secondary port with the inlet port, and, in the other direction, to establish communication of the secondary port with the exhaust connection, whereby the secondary or transformed pressure in the supply passage is varied; a movable abutment provided with a piston area; a thrust bearing between one end of the piston valve and the abutment; means providing for the application of fluid under primary pressure to the abutment piston area; biasing means having its force acting on the abutment in opposition to the force of the primary pressure; means providing a secondary piston area on the piston valve; means for supplying fluid under secondary pressure to the secondary piston area; said secondary piston area being so disposed that, with movement of the piston valve in consequence of primary pressure change, the force of the resulting secondary pressure is effective to restore the piston valve to neutral or cut-off position; and means for imparting spinning motion to the piston valve.

2. In combination, means providing fluid under primary pressure; a cylinder having an inlet port supplied with fluid under pressure, an exhaust connection, and a secondary pressure port; means providing a supply passage communicating with the secondary port; a piston valve movable from an intermediate cut-off position, in one direction, to establish communication of the secondary port with the inlet port, and, in the other direction, to establish communication of the secondary port with the exhaust connection, whereby by secondary or transformed pressure of fluid in the supply passage may be varied; an abutment; a thrust bearing between one end of the piston valve and the abutment; said abutment having a piston area at the thrust bearing side thereof; means providing for the application of fluid un-

der primary pressure to said piston area; a spring acting on the abutment in opposition to the primary pressure; means providing a secondary piston area on the piston valve; means for supplying fluid under secondary pressure to the secondary piston area; said secondary piston area being so disposed that, with movement of the piston valve in consequence of primary pressure change, the force of the resulting secondary pressure is effective to restore the piston valve to neutral or cut-off position; and means utilizing fluid under pressure for spinning the piston valve and including a turbine rotor carried directly by the latter.

3. In combination, means providing fluid under primary pressure; a cylinder having an inlet port supplied with fluid under pressure, an exhaust connection, and a secondary pressure port; means providing a supply passage communicating with the secondary pressure port; a piston valve movable from an intermediate cut-off position, in one direction, to establish communication of the secondary pressure port with the inlet port, and in the other direction, to establish communication of the secondary pressure port with the exhaust connection; an abutment providing a primary piston area; a thrust bearing between one end of the piston valve and the abutment; means cooperating with the abutment to define a fluid-tight compartment whose interior surface is provided in part by the primary piston area; means for supplying fluid under primary pressure to said chamber; a spring acting on the abutment in opposition to the primary pressure; means providing a secondary piston area on the piston valve and facing in such a direction that pressure applied thereto causes the piston valve to follow the motion of the abutment; means providing for the application of fluid under secondary pressure to said secondary piston area; and means for imparting spinning motion to the piston valve.

4. In combination, means providing fluid under primary pressure; a cylinder having an inlet port supplied with fluid under pressure, an exhaust connection, and a secondary pressure port; means providing a supply passage communicating with the secondary pressure port; a piston valve movable from intermediate cut-off position, in one direction, to establish communication of the secondary port with the inlet port, and in the other direction, to establish communication of the secondary port with the exhaust connection; an abutment; a thrust bearing between one end of the piston valve and the abutment; said abutment having a piston face at the thrust bearing side thereof; means for applying fluid under primary pressure to the abutment piston area; a spring acting on the abutment in opposition to the primary pressure; means providing a secondary piston area on the piston valve and facing in the same direction as that of the primary piston area; means for supplying fluid under secondary pressure to the secondary piston area; and means utilizing fluid under pressure for spinning the piston valve and including a turbine rotor carried directly by the latter.

5. In combination, means providing fluid under primary pressure; a movable abutment having a primary piston area subject to fluid under primary pressure; spring means acting on the abutment in opposition to the fluid under primary pressure; a cylinder having an inlet port supplied with fluid under pressure, an exhaust connection, and a secondary pressure port; means

providing a supply passage communicating with the secondary pressure port; a piston valve movable with the abutment to place the secondary pressure port in communication either with the 5 inlet port or with the exhaust connection to secure variation of fluid under secondary pressure in the supply passage; means providing a secondary piston area on the piston valve; means providing for the application of fluid under secondary pressure to the piston area; said secondary piston area facing in such a direction that the secondary pressure imposed thereon acts in a direction opposite to said spring means; a thrust bearing between said abutment and the adjacent 10 end of the piston valve; and means for imparting spinning motion to the piston valve.

6. The combination with a prime mover having an admission valve, of means for developing fluid under primary pressure which is a function of the prime mover speed; pressure supply means; a cylinder having an inlet port communicating with the pressure supply means, having an exhaust connection, and having a secondary or transformed pressure supply port; a piston valve 20 for placing the secondary pressure port in communication with the inlet port or with the exhaust connection to vary the secondary pressure; means for moving the piston valve including primary and secondary piston areas subject to primary 25 and secondary pressures, respectively, and biasing means whose force opposes the force of the primary pressure applied to the primary piston area; a servo-motor for adjusting said admission valve and including a pilot valve for controlling the admission and exhaust of motive fluid thereto; a pressure responsive device for moving the servo-motor pilot valve; a passage for supplying fluid under secondary pressure from said secondary pressure supply port to the pressure-responsive 30 device; and scale spring means exerting force on the servo-motor pilot valve such that a range of secondary pressures from a lower pressure to a higher pressure is required to move the pilot valve sufficiently to secure full range of movement of 35 the servo-motor in one direction and from the higher pressure to the lower pressure for such movement in the other direction.

7. The combination with a prime mover having an admission valve, of means for developing fluid under primary pressure dependent on the prime mover speed; a cylinder having an inlet port supplied with fluid under pressure, an exhaust connection, and a secondary pressure port; means providing a supply passage communicating with the secondary pressure port; a piston valve movable to establish communication of the secondary pressure port either with the inlet port or with the exhaust connection to provide a variable secondary pressure; a movable abutment having a primary piston area subject to primary pressure; a spring exerting its force on the abutment in opposition to that of the fluid under primary pressure; abutment means between one end of the piston valve and the movable abutment and including a thrust bearing; means providing a secondary piston area for the piston valve and so disposed that pressure exerted thereon tends to move the piston valve toward the movable abutment; means for imparting spinning motion to the piston valve; a servo-motor controlling said admission valve to admit steam to the prime mover suitable to the load and including a pilot valve; and means for actuating the pilot valve including 70 scale spring means and a device connected to said 75

supply passage and responsive to secondary pressure.

8. In combination, means providing fluid under primary pressure; a cylinder having an inlet port supplied with fluid under pressure, an exhaust connection, and a secondary pressure port; means providing a supply passage communicating with the secondary pressure port; a piston valve for placing the secondary pressure port in communication either with the inlet port or with the exhaust connection to secure variation in secondary or transformed fluid pressure; means for actuating the piston valve including primary and secondary piston areas; means for applying fluid under primary pressure to the primary piston area; means including an orifice for supplying fluid from said supply passage to said secondary piston area; and an accumulator in communication with the last-named means at the secondary piston area side of the orifice. 10 15 20

9. In combination, means providing fluid under primary pressure; a cylinder having an inlet port supplied with fluid under pressure, an exhaust connection, and a secondary pressure supply port; means providing a supply passage communicating with the secondary pressure port; a piston valve movable from an intermediate cut-off position, in one direction, to establish communication of the supply port with the inlet port, and, in the other direction, to establish communication of the secondary port with the exhaust connection; spring means for moving the piston valve in one direction; means responsive to fluid under primary pressure and acting in opposition to the spring means to provide movement of the piston valve in the other direction; means providing a secondary piston area on the piston valve; means for supplying fluid under secondary pressure to the secondary piston area and including an orifice; and an accumulator communicating with the last-named means at the secondary piston area side of the orifice; said secondary piston area being so disposed that, with movement of the piston valve in consequence of primary pressure change, the force of the resulting secondary pressure is effective to restore the piston valve to neutral or cut-off position. 30 35 40 45

10. In combination, means providing fluid under primary pressure, a pressure transformer utilizing fluid under primary pressure to provide a secondary or transformed fluid pressure, said transformer including primary and secondary piston areas, means for subjecting the primary piston area to primary pressure, means providing a delivery passage for fluid under secondary or transformed pressure, means providing a branch passage including an orifice for supplying fluid under secondary pressure from the delivery passage for action on the secondary piston area, and an air chamber communicating with the branch passage at the secondary piston area side of the orifice. 50 55 60

11. In a prime mover, admission valve means, means providing a primary fluid pressure varying as a function of the prime mover speed, means utilizing the primary pressure to provide a transformed or secondary pressure having normal predetermined relation with respect to the primary pressure, means responsive to transformed or secondary pressure to control the admission valve, means, and means responsive to exceeding a predetermined rate of primary pressure change and speed change to cause change of secondary pressure at a greater rate than that corresponding to the rate of primary pressure change to effect quick 70 75

adjustment of the valve means for normal speed of the prime mover for the load condition.

12. The combination with a turbine having admission valve means; of means for biasing the admission valve means in a closing direction; pressure responsive means for controlling the admission valve means; means for developing fluid under primary pressure which is a function of the turbine speed; a cylinder having an inlet port, 10 an exhaust connection, and a secondary pressure port; a passage for supplying fluid under high pressure to the inlet port; a piston valve movable to establish communication of the secondary pressure port either with the inlet port or with the exhaust connection to secure variation in transformed or secondary pressure; means for imparting spinning motion to the piston valve; means providing a primary piston area subject to primary pressure; abutment means between the means providing the primary piston area and one end of the piston valve and including a thrust bearing; a spring exerting its force on said abutment means in opposition to the force exerted thereon by the primary pressure; 20 means providing a piston area on the piston valve; means providing for the application of fluid under pressure to said secondary piston area; an overspeed governor operated by the turbine; and means responsive to operation of the overspeed governor to interrupt said high pressure passage and to release the pressure in the secondary passage, so that said biasing means may close the admission valve means.

13. The combination with a turbine having admission valve means; of means for biasing the admission valve means in a closing direction; pressure responsive means for controlling the admission valve means; means for developing fluid under primary pressure which is a function of the turbine speed; a cylinder having an inlet port, an exhaust connection, and a secondary pressure port; a passage for supplying fluid under high pressure to the inlet port; a piston valve movable to establish communication of the secondary pressure port either with the inlet port or with the exhaust connection to secure variation in transformed or secondary pressure; means for imparting spinning motion to the piston valve; means providing a primary piston area subject to primary pressure; abutment means between the means providing the primary piston area and one end of the piston valve and including a thrust bearing; a spring exerting its force on said abutment means in opposition to the force exerted thereon by the primary pressure; 25 means providing a secondary piston area on the piston valve; means providing for the application of secondary pressure to said secondary piston area; a branch passage supplied with fluid through an orifice from said high pressure passage and connected to the pressure responsive means of the throttle valve; a pressure release passage connected to said secondary passage; a normally closed valve in the release passage; a normally open valve in said high pressure passage between said branch connection and said cylinder; a pressure responsive device connected to said branch passage and effective normally to maintain the release passage valve closed and to maintain the 30 high pressure passage valve open; an overspeed governor operated by the prime mover; and means responsive to operation of the overspeed governor at a predetermined overspeed of the prime mover to release the pressure in said branch passage 35 to bring about closure of the throttle valve, closing of said high pressure passage valve, and opening of said secondary release passage valve so that said biasing means may close the admission valve means.

14. The combination with a prime mover having admission valve means and a throttle valve, of biasing means for closing the admission valve means; pressure responsive means for controlling the admission valve means; means responsive to pressure for holding the throttle valve open against the force of biasing means; means for developing fluid under primary pressure 10 which is a function of the prime mover speed; means including a passage providing a source of fluid under high pressure; a secondary pressure supply passage connected to said admission valve controlling means; a cylinder having high 15 pressure, secondary pressure, and exhaust connections; said high pressure and secondary pressure connections being connected to the high pressure and secondary pressure passages; a piston valve movable in opposite directions in said 20 cylinder to place the secondary pressure connection in communication either with the high pressure connection or with the exhaust connection; means for imparting spinning motion to the piston valve; means providing a primary piston area 25 subject to primary pressure; abutment means between the primary piston area providing means and one end of the piston valve and including a thrust bearing; a spring exerting force on the primary piston area in opposition to the force 30 exerted thereon by the primary pressure; means providing a secondary piston area on the piston valve; means providing for the application of secondary pressure to said secondary piston area; a branch passage supplied with fluid through an 35 orifice from said high pressure passage and connected to the pressure responsive means of the throttle valve; a pressure release passage connected to said secondary passage; a normally closed valve in the release passage; a normally open valve in said high pressure passage between said branch connection and said cylinder; a pressure responsive device connected to said branch passage and effective normally to maintain the release passage valve closed and to maintain the 40 high pressure passage valve open; an overspeed governor operated by the prime mover; and means responsive to operation of the overspeed governor at a predetermined overspeed of the prime mover to release the pressure in said branch passage 45 to bring about closure of the throttle valve, closing of said high pressure passage valve, and opening of said secondary release passage valve so that said biasing means may close the admission valve means.

15. The combination with a prime mover having an admission valve moved by a servo-motor and having means for developing fluid under pressure which varies as a function of the prime mover speed, of means responsive to said fluid pressure to provide transformed fluid pressure bearing predetermined relation with respect thereto, a passage for supplying fluid under transformed pressure to the servo-motor to control the operation of the latter, means providing an orifice in said passage to restrict the flow rate therethrough, and accumulator means in communication with said passage between the orifice and the servo-motor.

16. The combination with a prime mover having an admission valve moved by a servo-motor and having means for developing fluid under primary pressure which varies as a function of the prime mover speed, of pressure supply means, a passage for supplying fluid under secondary pres- 70

sure to said servo-motor, an exhaust connection, a piston valve for placing the secondary pressure supply passage in communication with said supply means or with the exhaust connection, means 5 for imparting spinning motion to the piston valve, means for actuating the piston valve including primary and secondary piston areas subject to said primary and secondary pressures, respectively, a passage for supplying fluid from the sec-

ondary passage to the secondary piston area and provided with an adjustable orifice, an accumulator in communication with said supply passage between the orifice and the secondary piston area, an adjustable orifice in the secondary supply passage, and an accumulator communicating with the secondary supply passage between the last-named adjustable orifice and the servo-motor.

ANTHONY F. SCHWENDNER.
